LEE J. BLACK, OF BEAUMONT, TEXAS

DOUBLE-TAPERED SLIP FOR ROTARIES

Application filed February 11, 1930. Serial No. 427,614.

This invention relates to the slips or pipe holding members commonly adapted to be seated in the rotary table of a rotary drilling machine having a downwardly converging seat and the general object of the present invention is to provide a slip of this character which includes a jaw carrier having an inclined rear face adapted to fit against the bowl or seat of a rotary table and a wedge 5 movable downward in the carrier and having interlocking engagement therewith, the wedge being adapted to engage a pipe or other concentrically disposed body, the wedge and carrier being capable of being moved 10 together out of the bowl or slip seat of the rotary table and the wedge being adapted to be raised or lowered to a limited extent independently of the carrier.

A further object is to provide a mechanism 20 of this character wherein a handle is provided so connected to the carrier and to the wedge that the wedge and carrier may both be lifted unitarily out of the bowl of the rotary or both be lowered into said bowl while 25 at the same time the wedge may be independently raised or lowered within certain limits.

A further object is to provide a slip comprising a plurality of carriers hingedly connected to each other for swinging movement 30 and provide each of said carriers with a corresponding vertically shiftable wedge carried by the carrier and provide single means connected to certain of the carriers and to all of said wedges whereby the carriers as a unit 35 may be lifted into or out of the bowl of the rotary and whereby the wedges of the carriers may be independently shifted up or down to a limited extent.

A further object is to provide improved 40 anti-friction means disposed between each wedge and the corresponding carrier.

Other objects will appear in the course of the following description.

My invention is illustrated in the accompanying drawings, wherein:—

Figure 1 is a top plan view of a slip comprising a plurality of carriers or wedges constructed in accordance with my invention;

Figure 2 is a fragmentary vertical section 50 of the upper portion of the carrier and the

wedge on the line 2—2 of Figure 1, Figure 3 being a section in the same plane as Figure 2, but of the lower portion of the same carrier and wedge;

Figure 4 is a vertical sectional view 55 through a portion of the bowl of the rotary showing a carrier and wedge in elevation, the section being taken on the line 4—4 of Figure 1;

Figure 5 is a fragmentary top plan view 60 of the adjacent portions of two carriers showing the hinged connection between the carriers;

Figure 6 is a vertical section on an enlarged scale on the line 6—6 of Figure 5 65 through the two adjacent carriers and showing the hinge connection between the two portions;

Figure 7 is a view of the lubricating plate.

Referring to these drawings and particularly to Figures 1, 2, 3 and 4, 10 designates 70 a plurality of sections or carriers connected to each other to form a slip.

As illustrated, the slip shown in Figure 1 is formed of four of these sections or carriers 75 10, but it will be understood that it might consist of three of these sections or carriers of a greater number than four. The slip as shown is approximately semi-circular in form and it will be understood that under these 80 circumstances, two slips will be used within the bowl A of the rotary, which bowl is shown in section in Figure 4. Each of the carriers 10 is hollow as at 11. The outer face of each section or carrier 10 is downwardly and inwardly inclined as at 12 (see Figures 2 and 3). The inner face of each carrier is also downwardly and inwardly inclined but the inclination of this inner face is less than the inclination of this outer face 12. The inner 90 face of the carrier is formed with a dovetailed recess designated generally 13 in Figure 1 and shown in dotted lines and the inner wall of this recess is counter-recessed as at 14 as shown most clearly in Figures 2 and 95 3 for the reception of a plate 15 having apertures 16 within which grease or other lubricant can be placed, this plate, therefore, constituting anti-friction means. This plate has its outer face flush with the inner face of 100

the recess 13. Disposed within this recess 13 and slidably vertically therein is a jaw or wedge 17, having vertical side faces, the outer face of which may be either toothed or plain, this wedge being dove-tailed in cross section 5 so as to fit the dove-tailed recess 13 and permit the vertical movement of the wedge relative to the carrier 10, but preventing any other movement of the wedge. The downward movement of the wedge is stopped by 10 the shoulder 13^a forming the lower wall of the recess 13 as shown in Figure 3. Of course, the wedge may move upward relative to the carrier 10 to any degree desired. 15 Each wedge 17 adjacent its upper end is formed with a flange 18 which is adapted to seat upon the upper end face of the corresponding carrier and above this flange each wedge or jaw 17 has an upwardly extending lug 19. There are thus, in the construction 20 shown in Figure 1, four of these carriers 10 and four wedges or jaws, one slidably mounted in each carrier. The carriers are pivotally connected to each other as will be 25 hereafter described.

Passing loosely through the several lugs 19 is an arcuate rod 20, this rod being held in place within the several lugs and from any rotary movement of the rod relative to 30 each lug by means of the cotter pins 21 which extend through the lug and loosely through the rod from front to rear. This rod 20 is designed to be connected to the slip whereby the rod and corresponding wedges may be 35 lifted or lowered relative to the carriers 10. To this end, I form, as shown in Figure 1, upon adjacent carriers 10, the upwardly extending lugs 22. The handle 23 at its lower end is formed with a collar 24 through which 40 the rod 20 passes as shown in Figure 4. This handle is operatively connected by a chain 25 or other flexible elements to a pin or bolt 26 extending through the lugs 22, this bolt being detachable. Preferably, the handle 23 45 is provided with a hand hold 27 at its upper end.

It will be seen, particularly from Figure 4, that with this construction, the slip comprising the several carriers and their corresponding wedges can be lifted bodily out 50 of the bowl A or lowered bodily into the bowl A, but that when the slip has been lowered into the bowl, the jaws of the several carriers may be raised or lowered independently of the carriers to thus secure certain 55 advantages which will be stated more fully later. This is secured by the flexible connection 25 between the handle 23 and the carriers which permits the independent movement of the handle 23 for a limited distance. 60

While I do not wish to be limited to any particular means for pivotally connecting the carriers to each other, I have shown a hinged connection between the carriers. 65 This as illustrated in Figures 5 and 6 consists

in recessing the side face of one carrier as at 28 and forming the complementary carrier with an ear 29 projecting into the recess 28, the upper wall of the recess 28 forming an ear 30 as will be clear from Figure 6. The ear 70 29 is perforated as at 31. Disposed within the ear 30 is a bushing 32 which fits snugly within said ear and which extends downward below said ear 30 into a recess 33 formed in the upper face of the portion 29. This recess 33 is circular in plan view, but is of larger diameter than the diameter of the lower portion of the bushing 32. A bolt 34 passes downward through the bushing 32, downward through the aperture 31 in the ear 29 80 and carries at its lower end the nut 35 which bears against the under face of the ear 29. The aperture 31, it will be noted, is larger in diameter than the diameter of the bolt and thus while the bolt 34 and the bushing 32 are 85 fixed relative to one of the carriers 10, the other carrier 10 is shiftable in a plurality of directions upon the bushing and bolt, thus securing that flexibility of engagement between the sections or carriers which is necessary to a proper operation of these slips in 90 actual use.

The lower ends of the carriers are connected to each other in approximately the same manner as the upper end, one of the carriers having the ear 36 carrying the bushing 37 and a bolt 38 passing through the bushing, the other carrier having an ear 39 larger than the bushing and through which the bushing passes, there being washers 40 at opposite 100 ends of the bolt. Thus the upper and lower ends of a carrier 10 are hingedly connected to the upper and lower ends of the opposite carrier.

It will thus be seen that the wedges or jaws are so mounted as to allow for flexing with the carrier sections of the slip. I have illustrated the wedges as being limited in their downward movement by the shoulders 13^a. I do not wish to be limited to the use of these 110 shoulders, however, as obviously the flanges 18 will limit the downward movement of the wedges. In either case, there is a positive stop for the wedge or jaw. In Figure 4, the wedge or jaw 17 is shown in up position, as 115 it will be when the slips are placed in the slip bushing or bowl around the section of the pipe to be held. The outer taper of the carrier sections is made to fit the standard slip bushing bowl and is sufficiently tapered to 120 prevent the carriers from sticking when the pipe is raised.

The mechanism is used as follows:—When the unit is lifted by the handle 23 for the purpose of placing the unit in the slip bushing, the wedges or jaws 17 will slide up until the flexible connection 25 becomes taut, this flexible connection being attached to the carriers only and the wedges being connected to the handle only. When the unit is placed in the 130

slip bushing, the outside taper will force the carriers forward, putting the wedges 17 into engagement with the pipe in their up position. When the weight of the pipe is released, the wedges 17, being of less taper, will slide downward with the pipe, producing a very much greater wedging effect than can be had by the greater outside taper of the carriers. Therefore, it will not be necessary to cut teeth in the wedges or jaws that contact against the pipe, thus eliminating the cutting of the pipe which is now the case if the pipe should slip or rotate in the present toothed wedges or jaws.

When the pipe is lifted, the wedges 17 will follow the pipe up sufficiently to release the pressure on the carriers and the raising up of the handle 23 will automatically hold the wedges up and the unit can be easily lifted from the taper bushing.

The advantages of my construction are that it permits smooth faced wedges or jaws to be used instead of toothed wedges or jaws. These smooth faced wedges will not cut the pipe. I provide means for automatically releasing the jaws when the pipe is lifted. At the same time I prevent the slip pipe unit from sticking in the bushing or bowl and thus lift up the rotary bushing when the pipe is lifted. I secure a greater wedging effect to hold pipe because of the different tapers on carriers and wedges and I have provided means whereby the lift on the wedges or jaws is unitary.

In my construction, both the carrier and the wedges or jaws lift out as a unit when the handle is raised to the up position. The whole assembly, therefore, can be lifted clear of the bowl or bushing A. It will be seen that the method of joining two sections or carriers 10 to each other is such that one of the carriers is radially movable relative to the bushing and bolt but this bushing and bolt moves with the other of the carriers. This permits the adjustment of the slips radially, but prevents any great adjustment vertically.

While I have illustrated certain details of construction, I do not wish to be limited thereto, as obviously many minor changes might be made without departing from the spirit of the invention as defined in the appended claims.

I claim:—

1. A slip section for rotary well drilling rigs including a carrier adapted to be placed within the usual bowl and having a downwardly and inwardly inclined outer face to engage said bowl and a downwardly and inwardly incline inner face having a greater inclination than the outer face, a jaw having sliding, interlocking engagement with the last named face, and a handle directly connected to the jaw and a flexible connection between the handle and said carrier whereby to permit the handle to raise or lower both jaw and car-

rier when the flexible connection is taut and permit limited vertical movement of the jaw relative to the carrier when the flexible connection is slack.

2. A slip for rotary well drilling rigs including a plurality of segmental carriers operatively engaged one with another and adapted to be disposed within the usual bowl, each carrier having a downwardly and centrally inclined outer face to engage said bowl and a downwardly and centrally inclined inner face, a jaw for each carrier having sliding engagement with the inner face thereof, and means common to all of said carriers whereby the carriers and their corresponding jaws may be raised or lowered as a unit and whereby all of the jaws of the several carriers may be shifted vertically within the carriers for a limited distance.

3. A slip for rotary well drilling rigs including a plurality of segmental carriers adapted to be placed within the usual bowl, the carriers being hingedly connected one to another and each carrier having a downwardly and centrally inclined outer face and a downwardly and centrally inclined inner face, a jaw for each carrier having dove-tailed engagement with the carrier for vertical movement of the jaw within the carrier, and a single handle operatively connected to the several carriers and operatively connected to the several wedges, the operative connection between the handle and the carriers permitting the handle and the connected jaws to have limited vertical movement with reference to the carriers.

4. A slip for rotary well drilling rigs including a plurality of segmental carriers adapted to be placed within the usual bowl, the carriers being hingedly connected one to another, and each carrier having a downwardly and centrally inclined outer face and a downwardly and centrally inclined inner face, a jaw for each carrier having dove-tailed engagement with the carrier for vertical movement of the jaw within the carrier, and a single handle operatively connected to the several carriers and operatively connected to the several wedges, the operative connection between the handle and the carriers being flexible whereby to permit the handle and the connected jaws to have independent vertical movement with relation to the carriers.

5. A slip for rotary well drilling rigs including a carrier having its outer face inclined downward and inward to fit within the usual bowl and having its inner face similarly inclined, a jaw having sliding, interlocking engagement with the inner face of the carrier, anti-friction means disposed between the confronting faces of the jaw and carrier and including a plate-like member disposed between the confronting faces, the carrier being recessed to support said member.

6. A slip for rotary well drilling rigs in-

cluding a carrier having its outer face inclined downward and inward to fit within the usual bowl and having its inner face similarly inclined, a jaw having sliding, interlocking engagement with the inner face of the carrier, anti-friction means disposed between the confronting faces of the jaw and carrier, including a plate-like member disposed between the confronting faces and having apertures to be filled with grease, the face of the carrier being recessed to receive said plate-like member.

7. A slip for rotary well drilling rigs including a plurality of segmental carriers operatively connected one to another, a plurality of jaws one for each carrier, each jaw being slidably mounted on the inner face of the carrier, said inner face being downwardly and centrally inclined, a handle, a member connected to all of the jaws and upon which the handle is mounted, and a flexible element connecting said handle to the slip.

8. A slip for rotary well drilling rigs including a plurality of segmental carriers operatively connected one to another, a plurality of jaws one for each carrier, each jaw being slidably mounted on the inner face of the carrier, said inner face being downwardly and centrally inclined, a handle, an arcuate rod passing through the upper ends of all of the jaws and to which the handle is connected, and a flexible connection between said handle and the slip.

9. A slip for rotary well drilling rigs including a plurality of segmental carriers operatively connected one to another, a plurality of jaws one for each carrier, each jaw being slidably mounted on the inner face of the carrier, said inner face being downwardly and centrally inclined, a handle, an arcuate rod passing through the upper ends of all of the jaws and through the handle, and a flexible connection between the handle and the slip.

10. A slip for rotary well drilling rigs including a plurality of segmental carriers operatively connected one to another, a plurality of jaws one for each carrier, each jaw being slidably mounted on the inner face of its carrier, said inner face being downwardly and centrally inclined, a handle, an arcuate rod passing through the upper ends of all of the jaws and through the handle and a flexible connection between the handle and the slip, comprising lugs extending upward from adjacent carriers at the middle of the slip, a pin passing through said lugs, and a flexible element connected at one end to the handle and at its opposite end to said pin.

60 In testimony whereof I affix my signature.
LEE J. BLACK.
